Fig. 3

FIG. 1 is a side elevational view of a liquid filter embodying the new design.

FIG. 2 is a top plan view of the filter of FIG. 1.

FIG. 3 is a bottom plan view of the filter, showing non-essential features in broken lines.

FIG. 4 is a perspective view of the top of the filter, and

FIG. 5 is a sectional view as if on the line 5—5 of FIG. 2, showing the outer contour of the filter along that line.

The dominant features of the design reside in the portions shown in solid lines, which portions are characterized by the configuration of the top surface and the depressions around the periphery at the top, as best seen in FIGS. 1, 2 and 4.

I claim:

The ornamental design for a liquid filter, substantially as shown and described.
